United States Patent Office

Des. 181,878
Patented Jan. 7, 1958

181,878

HANDBAG

Lorena Pat Reed, New York, N. Y.

Application May 13, 1957, Serial No. 46,111

Term of patent 7 years

(Cl. D87—3)

Fig. 1 is a rear elevational view of a handbag embodying my new design;

Fig. 2 is a front elevational view thereof;

Fig. 3 is an end elevational view, and

Fig. 4 is a front perspective view of the handbag.

I claim:

The ornamental design for a handbag, as shown.
